(57) **CLAIM**

The ornamental display panel assembly design, as shown and described.

DESCRIPTION

FIG. 1 is a front, top and right side perspective view of a display panel assembly, showing the new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a rear, top and left side perspective view thereof;

FIG. 9 is an enlarged fragmentary view of the upper left corner on the front shown in FIG. 2; and,

FIG. 10 is an enlarged fragmentary view of the upper right corner on the rear shown in FIG. 3.

The dashed broken lines show portions of the display panel assembly that forms no part of the claimed design. The dot-dot-dash broken lines represent the boundaries of the claim and form no part thereof.

1 Claim, 8 Drawing Sheets
